UNITED STATES PATENT OFFICE.

GEORGE W. BALDRIGE, OF ST. LOUIS, MISSOURI.

TYPE-WRITING MACHINE.

SPECIFICATION forming part of Letters Patent No. 375,251, dated December 20, 1887.

Application filed June 28, 1886. Serial No. 206,411. (No model.)

To all whom it may concern:

Be it known that I, GEORGE W. BALDRIGE, of the city of St. Louis, in the State of Missouri, have invented a certain new and useful Improvement in Type-Writing Machines, of which the following is a full, clear, and exact description, reference being had to the accompanying drawings, forming part of this specification, and in which—

10 Figure 1 is a vertical transverse section through the keys of a type-writer, such as is shown in my application filed June 1, 1886, No. 203,814, the carriage and other parts being shown in elevation. Fig. 2 is an enlarged 15 detail perspective view of the rack-dogs and part of the rack. Fig. 3 is a side view showing part of the lining-bar and the mechanism for operating it. Figs. 4, 5, and 6 are sections taken on line 4 6, Fig. 1, showing the parts in 20 different positions. Figs. 7, 8, and 9 are end views of the carriage, showing the parts in different positions. Fig. 10 is a perspective view of the same and of the carriage as shown in Figs. 7, 8, and 9. Fig. 11 is a perspective view of the twin dog.

25 My invention relates to certain improvements in type-writing machines; and my invention consists in features of novelty, herein-after fully described, and pointed out in the 30 claims.

Referring to the drawings, A represents part of the frame, and B the keys of the machine. I have not shown a complete machine, as it is unnecessary to a clear understanding of my 35 present invention.

40 Represents the carriage provided with rollers C' C, between which the paper passes, as usual. The carriage is supported by and travels in grooved rollers C'. It is moved forward in printing by mechanism hereinafter described, and it may be moved back (when another line is to be printed) by means of a spring, E, inclosed in a case, E', and connected to the carriage in any suitable way. The spring E 45 is similar to the spring used to move the carriage forward in other type-writers; but in my present invention this spring is employed to bring the carriage back instead of moving it forward. The carriage is provided with a 50 rack or toothed bar, D. Engaging with the notches of the rack is a dog, D', secured to the

frame of the machine by an arm, D², and held into engagement with the teeth by a spring, D³, secured to the arm. (See Figs. 1 and 2.) In like manner there engages with the teeth 55 of the rack a dog or pawl, D⁴, pivoted to the upper end of a bell-crank lever, D⁵, and held into engagement with the notches by means of a spring, D⁶, secured to the lever, as shown in Figs. 1 and 2. The lever is pivoted at D⁷ to 60 the frame of the machine, and it is connected to the frame by a spring, D⁸.

D¹⁰ represents a bar extending under all of the keys, and to which the lower end of the bell-crank lever D⁵ is connected by means of a 65 rod, D¹¹, as shown in Fig. 1. All of the letter, character, numeral, and spacer keys B of the machine operate this bar D¹⁰, and in doing so operate the lever D⁵. When the lever is thus operated, the dog or pawl D⁴ is made to slip 70 over one or more of the teeth of the rack, and then, when the key operated is released, the spring D⁶ will pull the carriage forward the distance of the number of teeth passed over by the dog or pawl, as stated. As the dog or 75 pawl is thus pulled back to engage a fresh tooth, the carriage is prevented from being pulled back under the influence of the spring E by means of the dog or pawl D⁴, and then, as the spring D⁶ pulls the carriage forward, as 80 stated, the dog or pawl D⁴ slips over the teeth, allowing the movement of the carriage. The spring D⁶ must of course be made sufficiently strong or with sufficient tension to overcome the spring E and cause the movement of the 85 carriage when a key has been released after operating the lever D⁵ and dog D⁴. The spring pulls the lever and dog over until it brings the lever against a stationary stop, D¹².

As clearly pointed out in the specification 90 of my application above referred to, it is desirable to have more or less space for different letters or characters—as, for instance, the letter "I" requires less space than the letter "L," and the letter "L" requires less space 95 than the letter "M," &c. With my present invention this spacing for the different letters is accomplished in a cheap and effective manner.

The keys B are notched at B', as shown in 100 Fig. 1, so that they will operate to move the bar D¹⁰ a greater or less distance, according to

the space required, the key of the letter "I" not operating the bar so far as the key of the letter "L," and the key of the latter letter not operating the bar so far as the key of the letter 5 "M," and so on, the notches B being made the proper length to give this result, the notch, for instance, in the key of the letter "I" being longer than the notch in the key of the letter "N," and the notch in the key of the latter letter being longer than the notch in the key of the letter "M," and so on, or the key of a letter the space of the letter "M" need not be notched at all, and the other keys be notched, as required.

15 Now the operation is this: When the key of the letter "I" (or of a letter requiring the same space) is operated, the bar B is depressed sufficiently to cause the pawl or dog D⁴ to engage the next tooth to the one occupied by it. This 20 will cause the carriage to be moved forward the distance of one tooth. When the key of the letter "N" (or letter requiring like space) is operated, the bar will be depressed farther than before, so that the dog D⁴ will engage the 25 second notch behind the one occupied by it, and when this key is released the carriage will of course be moved forward the distance of two notches, thus giving the required space for this letter, or for a letter requiring a like 30 space. Now when the key of the letter "M" (or of a letter requiring like space) is operated, the dog or pawl D⁴ will be made to engage the third notch from the one last occupied by it, and the carriage will now be moved forward 35 the distance of three notches, and thus the required space be given for this letter. This method for giving the various spaces to the letters requiring more or less room will at once be seen to be cheap and effective in performing its functions. When a line or part of 40 a line has been written and it is desired to return the carriage to its forward position to commence another line, it is of course necessary that the dogs or pawls D⁴ be disengaged 45 from the rack D, and when thus disengaged the carriage is returned by the spring E. As a means for disengaging the dogs from the rack D, I have shown a lining-bar rail or plate, F, pivoted to the carriage at F' by arms F², 50 the plate being held and working in slots G of the ends C⁴ of the carriage, and held in its upper position by a spring or springs, H, (see Figs. 7, 8, and 9,) which connect it or the arms F² to the ends C⁴ of the carriage. Fitting 55 over this plate or rail is a grooved stationary pulley, I, journaled in the upper end of a plate or arm, I', the plate or arm extending downward and being connected at I' to a key, J, which is preferably located in the center of the machine, as shown in Fig. 1, and which is notched out at J', so as not to come in contact with and operate the bar D¹⁰. Pivoted to this plate at I' is an arm, L, provided with wings L², which engage over projections 60 D¹³ on the dogs D⁴ and D⁴, when the arm is held out into its normal position, by a spring, L², as shown in Figs. 3, 4, and 6. Now it will

be seen that when it is desired to return the carriage, after the completion of a line or part of a line, it is only necessary to press on the 70 key J, when the arm L, being pulled down, will disengage the dogs from the carriage, as shown in Fig. 6, and the carriage is free to be moved back. As soon as the key J is released, the arm L, plate I, and rail F (which 75 have been moved down with it) are returned to their normal position by the spring or springs H, and the dogs again engage the rack of the carriage.

When a line has been written, it is of course 80 necessary to turn the roller C² of the carriage to feed the paper forward for a new line. This is done with my invention when the dogs are disengaged from the carriage, as just described, by means of an elongated pawl, M, connected 85 to an extension, F⁴, of one of the arms F², as shown in Figs. 7, 8, 9, and 10. This dog or pawl engages a ratchet-wheel, C⁵, on one end of the roller C², and it will be seen that when the rail F is lowered this pawl will cause the 90 turning of the roller C² through means of its connection with the arm F², and consequently with the rack, and when the rail F rises the pawl M will slip over and engage the next tooth of the ratchet-wheel C⁵, so as to move 95 the roller another notch the next time the rail F is operated. This elongated pawl is made sufficiently thin to allow it to spring without operating the plate or rail F when pressed from above, so that when it is desired to turn 100 the roller C² without operating the rail F it can be done by simply pressing on a knob, M', on top of the pawl, and located there for that purpose. The movement of the pawl is checked, so that the roller will only move the 105 distance of one notch, by means of a sliding stop, N, dovetailed into blocks N', secured to the end C⁴ of the carriage beneath the ratchet-wheel, and provided with a knob, N², by which it may be moved, the pawl being formed with 110 a lug or projection, M², beneath the ratchet-wheel, that comes against this stop.

When it is desired to move the roller the distance of two notches, it may be done by simply moving the stop back from the position shown in Fig. 7 to that shown in Fig. 8, so that the lug or projection M² will not come in contact with it.

It is sometimes desired to turn the roller C² for a fresh line by means of the key J and 120 without disengaging the pawls from the rack, and to do this I have provided a means whereby at such times the arm L may be moved inward, compressing the spring L², so that it will not engage the projections D¹³ of 125 the dogs, as shown in Figs. 5 and 8. This means consists of a rod or bar, O, fitting in a slot, L⁵, of the arm L and provided with a cross-head, O', on its upper end, that fits upon the upper face of the arm. (See Fig. 3.) This 130 rod O is guided in keepers O² and extends down beneath the keys, terminating in a loop, O³, into which enters the inclined end P of a sliding bar or plate, P', held and guided in

support P². Thus, when it is desired to turn the roller C² by moving the rail F by the key J, and this without disengaging the dogs from the rack, the bar or plate P' is shoved from the position shown in Fig. 4 to that shown in Fig. 5, its inclined end bearing upon the bottom of the loop O³ and forcing the rod O and arm L downward, disengaging the latter from the projections D¹³, as shown in Figs. 5 and 8, so that the roller C can be turned without disengaging the dogs from the rack. When the rod or plate P' is pulled out again, the spring L³ returns the arm L and rod O to their normal position, so that the wings of the arm L will again engage the projections D¹³ of the dogs or pawls D' D⁴.

Though I show the pawl D' as in one piece or single, I prefer to make it double, or consisting of two parts, D^a D^b, (see Fig. 11,) the projection D¹³ being secured to one of the parts and fitting in a short slot, D²⁰, in the other part, and both parts being equal in width to the width of the teeth of the rack and both being held into engagement with the teeth of the rack by the spring D³. (See Figs. 1 and 2.) The distance between the points or ends of these two parts is equal to half the length of each tooth of the rack, and the object of the double dog is that, should one member fail to engage in the notch intended, the other member will engage the next tooth, and thus the carriage would be prevented from moving the distance of a whole tooth, but only be allowed to move the distance of half a tooth. A still less movement of the carriage could be prevented by having three or four parts to the dog.

Some other means than the dogs D' could be employed to prevent the retrograde movement of the carriage, and some other means than the spring E could be employed to move the carriage back.

I claim as my invention—

1. In a type-writer or similar machine, the combination, with the keys and a carriage having a rack, of the spring for retracting the carriage, dog D', dog-spring D³, fixed supporting-arm D², bell-crank lever D⁵, dog D⁴, dog-spring D⁶, lever-spring D⁷, stop D¹², rod D¹⁵, and bar D¹⁰.

2. In a type-writer or similar machine, the combination, with the carriage having a rack, of the pawls D' and D⁴, engaging the rack, having projections D¹³, the plate I', pivoted arm L, provided with wings L², for engaging the projections, spring L³, for throwing pivoted arm outward, and rod O, having cross-head O', for pressing the pivoted arm inward.

3. In a type-writer or similar machine, in combination with the spring-dog for causing the forward movement of the carriage, provided with a projection, a double dog provided with a projection secured to one of the parts and fitting in a slot in the other part, an arm engaging said projections, and mechanism, substantially as described, for operating the arm to

disengage the dogs from the rack of the carriage, substantially as shown and described.

4. In a type-writer or similar machine, the carriage provided with a main paper-roller, mechanism for turning the roller, consisting of a ratchet-wheel and pawl, plate or rail to which the pawl is connected, a rod provided with a pulley engaging with the plate, and a key to which said rod is connected for operating the parts, substantially as set forth.

5. In a type-writer or similar machine, in combination with a carriage provided with a main paper-roller and ratchet-wheel, a pawl engaging the ratchet-wheel, a plate to which the pawl is connected, a spring for holding the plate in its upper position, and mechanism, substantially as described, for depressing the plate, consisting of a rod provided with a pulley and an operating-key to which the rod is connected, substantially as set forth.

6. In a type-writer or similar machine, the combination of the carriage provided with a main paper-roller having a ratchet-wheel, a pawl engaging the ratchet-wheel, a plate pivoted to the carriage by means of arms, to one of which the pawl is connected, a spring for holding the plate in its upper position, and means, substantially as described, for depressing the plate, substantially as set forth.

7. In a type-writer or similar machine, in combination with a carriage provided with a main paper-roller having a ratchet-wheel, a pawl for engaging the wheel, and mechanism, substantially as described, for operating the pawl, consisting of a spring-plate to which the pawl is connected, and a key for operating the plate and to which the plate is connected, substantially as and for the purpose set forth.

8. In a type-writer or similar machine, in combination with the carriage having a main paper-roller provided with a ratchet-wheel, a flexible pawl engaging the ratchet-wheel, provided with a lug, M², beneath the ratchet-wheel, mechanism, substantially as described, to which the pawl is connected and by which it is operated, and a stop beneath the lug with which the lug engages for limiting the movement of the pawl, substantially as set forth.

9. In a type-writer or similar machine, in combination with the carriage provided with a main paper-roller having a ratchet-wheel, a pawl engaging the ratchet-wheel, provided with a lug, M², mechanism, substantially as described, to which the pawl is connected and by which it is operated, and a check for said pawl, consisting of a block having a sliding stop against which the projection on the pawl engages, substantially as shown and described, for the purpose set forth.

10. In a type-writer or similar machine, in combination with the carriage provided with a main paper-roller having a ratchet-wheel, a pawl engaging the ratchet-wheel, and mechanism for operating the pawl, consisting of a sliding plate, arms connecting the plate to the ends of the carriage, and to one of which the

40 said pawl is connected, operating-key, rod connected to the operating-key, and pulley on said rod engaging over said plate, substantially as shown and described, for the purpose set forth.

11. In a type-writer or similar machine, in combination with the carriage having a main paper-roller provided with a ratchet-wheel, and having a rack, dogs engaging said rack, a pawl engaging said ratchet-wheel, and mechanism, substantially as described, for operating said dogs, whereby when the dogs are disengaged from the rack the pawl turns the paper-roller, substantially as specified.

15 12. In a type-writer or similar machine, in combination with a main paper-roller having a rack, a ratchet-wheel, dogs provided with projections and engaging said rack, mechanism for disengaging said dogs, consisting, essentially, of an arm engaging said projections and a key to which the arm is connected and by which it is operated, a pawl engaging said ratchet-wheel, and mechanism for operating said pawl, consisting, essentially, of a plate and rod by which the pawl is connected to said operating-key, substantially as set forth.

13. In a type-writer or similar machine, in combination with the carriage provided with a rack and a main paper-roller having a ratchet-wheel, dogs provided with projections and engaging said rack, spring-arm having wings engaging the projections on the dogs, rod O, having a cross-head to which the arm is connected, operating-key to which the rod is connected, a plate, I', to which the arm is pivoted and which is connected to said operating-key, a bar having an inclined end for operating the rod to disengage the arm from the projections, pawl engaging the ratchet-wheel on the paper-roller, and mechanism, substantially as described, connecting the said pawl to said operating-key, the whole being arranged substantially as shown and described, whereby when a key is operated the dogs may be disengaged from the rack, or the 45 paper-roller turned without disengaging the dogs from the rack, substantially as set forth.
